UNITED STATES PATENT OFFICE.

LEVI G. WESTFALL, OF BEARDSLEY, MINNESOTA.

CHECKREIN-HOLDER.

No. 807,980.

Specification of Letters Patent.

Patented Dec. 19, 1905.

Application filed April 13, 1901. Serial No. 55,758.

To all whom it may concern:

Be it known that I, LEVI G. WESTFALL, a citizen of the United States, residing at Beardsley, in the county of Bigstone and State of Minnesota, have invented new and useful Improvements in Checkrein-Holders, of which the following is a specification.

My invention relates to checkrein-holders of harness; and it has for its primary object to provide a simple, inexpensive, and efficient checkrein-holder by which the rein may be easily and quickly secured.

The invention consists in the novel construction and combination of the several parts, as will be hereinafter fully set forth, and pointed out in the claim.

Referring to the accompanying drawings, Figure 1 is a vertical sectional view of my improved checkrein-holder clamping a checkrein. Fig. 2 is a rear view, the checkrein being in section.

Referring to the drawings, 1 designates the base-plate, having a slightly convex or cam surface 1^a, which is provided with transversely-extending serrations 2, providing teeth extending across the base-plate, and is also provided with holes 3, through which rivets may pass to secure the device to the crest of the saddle of the harness.

30 The plate 1 has its upper surface elevated gradually at an upward incline from opposite ends toward the serrations, the latter being located at the most elevated portion of the plate to render the bite on the checkrein more positive and effective as a securing means in conjunction with the device, which will be more fully hereinafter described.

Extending upward from opposite side edges of the plate 1 are a pair of standards 4, 40 provided adjacent to their upper ends with openings to receive a transverse pin 5, upon which is mounted the clamping-frame 6. This clamping-frame 6 is formed with side arms 6^a and connecting-webs 6^b and is provided with a cam-roller or a roller 7, eccentrically mounted on a pin 8 in the lower end of the arms 6^a beneath the connecting web and having longitudinal serrations 7^a.

50 The member 6 comprises opposite side arms 6^a and a front cross-web 6^b, which prevents the said arms from springing or yielding when the roller 7 is drawn into close clamping or securing position. It is obvious that without the web 6^b the arms 6^a would buckle, and the securing effect of the roller

would be impositive and unreliable. A further advantage of the said web is that lighter or thinner metal can be used in the construction of the entire member and adapts the latter to be struck up or formed from sheet metal, whereas if the web was not present the arms 6^a would have to be exceptionally heavy to withstand the strain brought to bear thereon.

9 designates a downwardly-extending extension projecting from the upper extremity of the connecting-web 6^b and serves as a finger-piece or trip for forcing the cam or roller 7 out of engagement with the strap or checkrein.

70 A spring 10 is mounted upon the transverse pin 5 and has one end bearing against the under side of the extension 9, and the other end is bent to form a hook, as at 11, and is fitted in a recess 12 in one of the supporting-standards. This spring serves to hold the clamping-frame in yielding engagement with the checkrein.

75 The operation of my device is as follows: The extension 9 is depressed, which swings 80 the clamping-frame 6 out of engagement with the serrated base. The checkrein is then placed in position upon said base-plate and pressure released on the extension of the clamping-frame, which, by reason of the 85 spring 10, will assume its normal position and clamp the checkrein securely.

It is obvious that the device may be used for other purposes than that of a checkrein-holder—such, for instance, as a holder for 90 ropes, strap, &c.

Having thus fully described my invention, what I claim as new, and desire to secure by Letters Patent, is—

95 In a device of the class described, a base-plate provided adjacent its ends with perforations for the reception of attaching devices and having adjacent to one of said perforations a serrated cam-surface, oppositely-disposed standards rising from the base-plate, a 100 pivoting-pin extending between and adjacent the upper ends of the standards, a three-sided swinging clamp comprising a connecting plate or web and a pair of flanged side arms formed integral with the web, said arms 105 being pivotally mounted at their upper ends upon the pivoting-pin and carrying at their lower ends a transverse supporting-pin, a serrated roller eccentrically mounted on said pin, the connecting web or plate of the frame 110

terminating at its lower end above the lower ends of the arms to provide a space below for the outward projection and reception of a portion of the body of the roller and cut away 5 at its upper end to form a finger-piece bent at a downward and rearward angle thereto, and a spring centrally coiled upon the pivoting-pin and having one of its arms projecting beneath and bearing upon the finger-piece and

its other arm removably interlocked with 10 one of the edges of one of the standards.

In testimony whereof I affix my signature in presence of two witnesses.

LEVI G. WESTFALL.
